UNITED STATES PATENT OFFICE.

SILAS MERRICK, OF NEW BRIGHTON, PENNSYLVANIA.

IMPROVEMENT IN RAILROAD-CAR TRUCKS.

Specification forming part of Letters Patent No. 38,973, dated June 23, 1863.

To all whom it may concern:

Be it known that I, SILAS MERRICK, of New Brighton, in the county of Beaver and State of Pennsylvania, have invented a certain new and useful Improvement in Side Bearings of Car-Trucks for Railroads, of which the following is a full, clear, and exact description, reference being had to the accompanying drawings, which make part of this specification, and in which—

Figure 1 represents a view in elevation of one side of so much of a car-truck embracing my improvement as is necessary to illustrate my invention; Fig. 2, a plan or top view of the same with the bolster removed; and Fig. 3, a view in elevation of the same as seen from the front, with the bolster in place.

My invention relates to that class of car-trucks which are provided with side bearings to render the motion of the car easy; and my improvement consists in mounting the friction-rollers forming the side bearings of the cars in guides curved in an arc of which the king-bolt forms the center, and allowing them end-play in their bearings to accommodate themselves to any lateral movement of the car.

In the accompanying drawings, which represent a convenient arrangement of parts for carrying out the object of my invention, the frame or body A of the truck is shown as provided with bearings B, which may be mounted upon wheels in any suitable manner. The car-body in this instance is firmly secured to the upper bolster, C, which rests upon a swinging bolster, D, which is suspended from the frame A by straps or radius-bars E, connected at bottom by a cross-piece, F, on which spiral springs G are mounted. As the tendency of these springs is to lift the swinging bolster, the weight of the car in effect rests upon them. The swinging bolster is prevented from jumping out of place by stoppins H underneath the frame. The king-bolt I passes through the floor of the car, the upper bolster, and the swinging bolster. Upon each end of the swinging bolster D a curved guide-box or bed-plate, J, is mounted and sustains a friction-roller, K. This friction roller

or wheel K may be of any suitable size, and is provided with a strong shaft, the journals of which rest upon the bed-plate, which has a smooth, flat surface, and is provided with posts or standards J at each corner of the bed-plate, so as to leave a space in which the wheel may roll on its bearings upon the bed-plate to accommodate itself to the swinging of the bolster when the car passes round a curve. The wheels are prevented from rising out of their bearings by proper top plates, J'. A corresponding guide, L, is mounted upon the upper bolster and fits upon the friction-roller, which has a slight degree of end-play in its bearings, to allow for the wear or play of the king-bolt. The roller and journals are shaped like the frustum of a cone, the greater diameter being outside, in order that it may more readily describe the arc of a circle round the king-bolt. Both the upper and lower guide-boxes are curved in the arc of a circle of which the king-bolt forms the center, by which means the parts are caused at all times to work harmoniously together. The edges of the upper guide boxes or flanges are slightly beveled, in order that they may readily readjust themselves to the rollers in case they should be displaced by the jolting of the car. The diameter of the wheel K is greater than that of its journals, and the flanged plate is firmly secured to the car-body bolster, and rests on the periphery of the wheel, while the smaller journals rest on the bed-plate of the truck-bolster, where there is less room for length of plate. This arrangement, it will be seen, allows the top plate to be of greater length than the bottom one, and, as it travels on the periphery of the wheel, it moves much farther than the journals on the bed-plate can traverse, and consequently gives a greater range of motion to the car. By this means it will be seen that both ends of the bolster are effectually supported, as well as its center, and that the several parts of the car and truck can readily adjust themselves to the varying circumstances under which they are required to operate.

Having thus described the construction and operation of my improved side bearing for car-

trucks, what I claim therein as new, and desire to secure by Letters Patent, is—

The combination of the guides J L, curved in the arc of a circle of which the king-bolt forms the center, with the conical friction-wheels K rolling upon a flat surface, and having end-play in their bearings, when constructed, arranged; and operating substan-

tially in the manner described, for the purposes set forth.

In testimony whereof I have hereunto subscribed my name.

SILAS MERRICK.
